UNITED STATES PATENT OFFICE.

WILHELM GUSTAV GROTHE, OF WEEESP, NETHERLANDS, ASSIGNOR TO C. J. VAN HOUTEN & ZOON, OF WEEESP, NETHERLANDS.

APPARATUS FOR DISCHARGING PRESS-BOXES IN HYDRAULIC PRESSES.

1,263,662.

Specification of Letters Patent. Patented Apr. 23, 1918.

Application filed May 24, 1916. Serial No. 99,669.

To all whom it may concern:

Be it known that I, WILHELM GUSTAV GROTHE, engineer, a subject of the Kingdom of the Netherlands, residing at Zandpad No. 5 25, Weesp, Netherlands, have invented certain new and useful Improvements in Apparatus for Discharging Press-Boxes in Hydraulic Presses; and I do hereby declare the following to be a full, clear, and exact 10 description of the invention, such as will enable others skilled in the art to which it appertains to make and use the same.

The present invention relates to an apparatus for discharging press boxes in hydraulic presses and has for its object to effect the discharging of the pressed cakes more rapidly and more easily than was possible with prior constructions.

In known presses with press boxes one 20 half of the number of press boxes is subject to pressure while the others are being emptied or filled. For the purpose of discharging, a strap is brought under the press box, which strap rests with its ends on the 25 frame. By means of a screw-threaded spindle arranged vertically in this strap, which spindle carries at its upper end a dished plate, by actuation of a hand crank, if desired, through the intermediary of a suitable 30 transmission gear, the freely supported base plate of the press box is raised with the 35 pressed cake located in the box whereupon the cake is removed in any suitable way. Similarly the remaining boxes are discharged one after the other.

As the strap is removed from beneath the press box at each operation and must be brought under the next press box, the operation involves a waste of time and in addition is rather fatiguing, because the strap is fairly heavy and the cakes are often very firmly bedded in the boxes. In addition, with heated presses the temperature of the 40 press and the vicinity of the press is very high which renders inconvenient operation among the press boxes.

These disadvantages are avoided by the present invention the novelty of which consists in the feature that beneath each of the 50 boxes, which are slid or swung to one side after the pressing operation and superposed, lifting arms are rotated and thereafter the lifting arms are simultaneously and mechanically or hydraulically raised and the 55 pressed cakes lifted from the boxes.

Apparatus for performing the said method in accordance with the present invention consists of a plurality of vertical spindles on which are mounted for free rotation lifting arms arranged one above the other and 60 which spindles are independently suspended in a hydraulic lifting device in such wise that the spindles with the lifting arms may be raised a distance corresponding to the height the pressed cake is to be lifted. 65

In the use of so-called double sided presses in which after a pressing operation the boxes are alternately slid or swung to one side and the other, and thereupon freshly filled boxes are slid or swung from the opposite side into the press chamber, the construction may be such that on both sides two groups of lifting arms can be brought into operative position, in which position they can be brought under the press boxes just 70 slid or swung out of the press chamber. 75

The spindles with the lifting arms are so arranged on the side of the press that the arms can be turned completely out of the service space to be occupied by the operator 80 and such space can be left free for the operator.

In the accompanying drawing is illustrated apparatus constructed in accordance with the present invention. 85

Figure 1 shows assembled a complete press with lifting devices; Fig. 2 is a vertical section of the press in a plane parallel to the picture plane in Fig. 1 with the press boxes partly in elevation and partly in section, with the pressure-head at the upper end in elevation. Fig. 3 is a horizontal section of a press above one of the pressing tables. Fig. 4 an elevation of the lower part of one of the spindles showing two 90 lifting arms and distance rings partly in section. Fig. 5 is a plan of the apparatus shown in Fig. 4. 95

The press shown in the drawing is adapted to be used for the removal of oil from 100 cacao. This press is of the vertical type and the pressing chamber *i. e.*, the chamber, where in the pressing operation the superposed press boxes with the pressed tables between the same are located, is provided at 105 the lower end with a hydraulic cylinder 1 and a ram 2 and with a pressure-head 3 at the upper end. The cylinder and head are connected by means of columns 4.

5, 6, 7, and 8 denote four cast iron frames 110

of which two are located at each side of the press, parallel to one another, and all of which are secured to the head 3 at the upper end and to the cylinder 1 at the lower end. On opposed sides of each frame are cast ledges with horizontal grooves 9. The boxes which are denoted by the numeral 10 are provided with ledges 11 adapted to engage the grooves 9. The grooves 9 are spaced equally apart and opposite each groove in one frame is a groove in the adjacent frame so that when the boxes are slid outward the boxes track the grooves 9 and are prevented from movement in upward direction.

For the purpose of supporting the boxes when they are located in the press chamber and thus out of operative relation with the grooves 9, there are cast on the lower side of the tables 12, between which the boxes are located in the pressing operation, ledges 14 which, on movement of the boxes into the pressing chamber, are each located at the same level as the part of the ledge below a groove 9 so that when the ledges on the boxes leave the grooves 9 they bear on the ledges 14. The boxes 10 are thus suspended as it were on the tables 12. The tables 12 are guided during the pressing operation on the columns 4, as will be understood from consideration of Fig. 3.

The boxes 10 have perforated base plates 15 (Fig. 2); on each base is located a filter plate 16 on which is laid the material 17 to be pressed; this material is again covered by a filter plate 18 and a perforated cover plate 19.

The pressing operation is effected by the rise of the ram 2, the cylindrical upper portion of the same and the cylindrical lugs on the tables 12 engaging the boxes and pressing the material therein. The butter flows through the perforations in the base plate 15 and the cover plate 19 and finally all that remains in each box is a so-called pressed cake.

The cacao press shown in the drawings has twelve boxes 10 of which six are in the pressing chamber proper, the other boxes are located alternately to the right and left thereof. When the boxes slid to the side are emptied and the pressing of the material in the other boxes has been effected, the latter will be moved aside to be discharged, that is, will be moved alternately to the left and to the right outside the pressing chamber, while the other boxes will be brought into operative position.

For the purpose of easy and speedy discharge there are provided two vertical spindles 20 and 21 mounted one on each side of the press adjacent to the frames 5 and 6 (Fig. 3). These spindles are supported at the lower end in fixed bushes 22, being supported in the lowest position by the collar

23 and prevented from rotation by means of the groove and feather 24. At the upper end each of the spindles is suspended in a fixed frame 25 by means of a hydraulic lifting device 26 and a hook which engages an eye on the spindle. On each spindle are mounted six rotatable or oscillatory arms 27, which arms are spaced apart by means of distance pieces 28.

The dimensions of the arms 27 and the position of the spindles 20 and 21 are such that the free end of each of these arms can be rotated exactly beneath one of the press boxes which has been slid to one side out of the press chamber for discharge. The operative position is shown at the right in Fig. 1 and in Fig. 5 in chain-dotted lines; in Fig. 2 there are shown at the right three boxes which have been slid to the side with the lifting arms thereunder. The free end of each arm is provided with a plate 29 (Fig. 4) which plate comes into position with the plane surface beneath the perforated base plate 15 of the box when the arm is located in operative position.

The spindles can be raised by the hydraulic lifting device 26 and assume the position shown at the left in Fig. 2. By the lifting of the spindles the plates 29 come first into contact with the base-plate 15 and on being further lifted raise the plates 15 and also the pressed mass.

The stroke is such that after the completion of the lifting operation the cakes are raised so far out of the boxes that they can be easily removed.

Thereafter the spindles are again lowered and fresh charges placed in the empty boxes. In the meantime the charges in the boxes located in the pressing chamber are pressed and the latter replaced by the boxes which have just been filled, such charged boxes being moved toward the center while the boxes in which the mass has been pressed assume the position in which they are filled. The lifting arms which have just effected their operation are in the interval swung to the side and now the intermediate arms are swung below the filled press boxes which are in turn duly discharged.

The means for lifting out the cakes in accordance with this invention can be adapted to existing presses in suitable manner without the necessity for altering the press itself. Also it is to be noted that the above described means can be used for lifting the cakes and for pressing in apparatus in which the boxes are not slideable but are mounted to swing about a vertical axis.

What I claim and desire to secure by Letters Patent of the United States of America is:—

1. Apparatus for discharging boxes in hydraulic presses, comprising a vertical spindle, arms mounted for oscillatory move-

ment on said spindle, and means for lifting said spindle and therewith said arms.

2. In a hydraulic press, in combination, boxes movable from within the press to discharging position outside the press, a vertical spindle alongside the press, arms mounted for oscillatory movement on said spindle, said arms provided with lifting members adapted, when the arms are oscillated in one direction, to assume a position beneath the boxes when in discharging position, and means for lifting said spindle and therewith said arms to discharge the boxes.
- 15 3. In a hydraulic press, in combination, a series of boxes movable from within the press to the exterior of the same and on opposite sides for discharging two vertical spindles, one on each side of the press, arms mounted for oscillatory movement on said spindle, said arms provided with lifting members adapted to assume a position be-

neath the boxes when in discharging position, and means for lifting said spindles and therewith said arms to discharge the boxes. 25

4. In a hydraulic press, in combination, a series of boxes movable outwardly from within the press to opposite sides of the same, vertical spindles contained in a vertical plane exterior to the press, arms mounted for oscillatory movement on said spindles and means for lifting said spindles and therewith said arms. 30

5. Apparatus for discharging boxes in hydraulic presses comprising arms mounted for oscillatory movement in a substantially horizontal plane, and means for lifting said arms. 35

In testimony whereof I affix my signature in presence of two witnesses,

WILHELM GUSTAV GROTHE.
